UNITED STATES PATENT OFFICE.

RUDOLPH SIEBERT, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

50,850.

Specification for Design.

Patented May 29, 1917.

Application filed March 23, 1917. Serial No. 157,027. Term of patent 3½ years.

To all whom it may concern:

Be it known that I, RUDOLPH SIEBERT, a citizen of the United States, and a resident of Rochester, Monroe county, State of New York, have invented a new, original, and ornamental Design for Buttons, of which the following is a specification.

My design is represented in the accompanying drawing, in which:

Figure 1 is a plan view of a button showing my new design.

Fig. 2 is a side elevation.

The button is circular in form. A projection extends upwardly from the central portion of its face, said face being roughened by a series of radially projecting curved lines, and the sides of which slope gradually to the periphery of the button. Mounted upon

this central projection is a mound shaped piece curved on its top surface, its base having a diameter slightly larger than the diameter of the projection upon which it rests. The surface of this central mound shaped projection is smooth.

I claim—

The ornamental design for a button substantially as shown and described.

In witness whereof I have hereunto set my hand at Rochester, in the county of Monroe and State of New York this 15th day of March, 1917.

RUDOLPH SIEBERT.

In presence of—

FRANK V. NEIDER,
EARL A. WELLER.
